UNITED STATES PATENT OFFICE.

HARPER F. SMITH, OF PHILADELPHIA, PENNSYLVANIA.

FLUID-PRESSURE REGULATOR OR GOVERNOR FOR VAPOR-LAMPS.

SPECIFICATION forming part of Letters Patent No. 759,035, dated May 3, 1904.

Original application filed April 30, 1903, Serial No. 154,970. Divided and this application filed June 20, 1903. Serial No. 162,310. (No model.)

To all whom it may concern:

Be it known that I, HARPER F. SMITH, a citizen of the United States, residing in the city and county of Philadelphia, State of Pennsylvania, have invented a new and useful Improvement in Fluid-Pressure Regulators or Governors for Vapor-Lamps, of which the following is a specification.

In a contemporaneously pending application filed by me April 30, 1903, Serial No. 154,970, for vapor-burners I have shown and described a novel construction of vapor-lamp and regulating device therefor, the claims therein being drawn to the construction of the lamp.

In the present application, which is a division of the above-mentioned application, I have shown, described, and claimed a novel construction of a governor wherein the parts are inclosed in a suitable casing, at the lower portion of which is located an oil or hydrocarbon chamber having a valved opening leading thereinto and an outlet therefrom whereby the hydrocarbon in predetermined quantities is conducted to the generating devices, the lower portion of the oil-chamber being provided with a suitable drip device. Above the level of the oil or hydrocarbon in the casing is located the vapor-chamber, to which the vapor from the generating devices is conducted by means of a suitable pipe, the vapor being withdrawn from the upper part of said chamber by means of a suitable connection which is controlled by a vapor-valve, whose action is regulated by the pressure of the vapor in said vapor-chamber upon a suitable diaphragm controlled by a spring adjacent thereto whose tension can be regulated according to requirements.

To the above ends my invention consists, broadly, in the novel construction of a fluid-pressure regulator which is particularly adapted for use in vapor-lamps, preferably constructed under my previous patents and pending application aforesaid, wherein the number of parts are reduced to a minimum and the construction simplified and cheapened throughout.

It further consists of other novel features of

construction, all as will be hereinafter fully set forth, and pointed out in the claims.

Figure 1 represents a vertical sectional view of a fluid-pressure regulator or governor embodying my invention, certain of the parts being shown in elevation. Fig. 2 represents a vertical sectional view of my novel construction of governor, showing also a vapor-lamp partly in section and partly in elevation, to which the same is applicable.

Similar numerals of reference indicate corresponding parts in the figures.

Referring first to Fig. 1, 1 designates a reservoir and casing for the governor, which may be of annular or other contour, as will be understood from Fig. 2, and is provided with a filler 2, whose upper portion is closed by a thumb-screw 3, provided with suitable packing 4 or other similar device. The casing 1 having been filled to the desired height it will be understood that the hydrocarbon may flow through the strainer-ports 5 and gauze 6 past the valve-seat 7, against the lower portion of which abuts the oil-valve 8, which has a stem 9 depending there from, which is surrounded by the coil or other spring 10, the upper portion of which abuts against the valve, while the lower portion of said spring is in contact with the head or closure 11, which has the port 12 therein closed by the plug 13, whereby the oil-chamber 14 can be emptied of sediment and the impurities may be removed therefrom according to requirements.

15 designates a pipe leading from, preferably, the upper portion of the oil or hydrocarbon chamber 14 to the generating device 85 of the lamp. Above the valve 8 and in opposite direction to the stem 9 projects the sleeve 16, which I have shown in the present instance as being integral with the valve, although it will be apparent that the same can 90 be made detached therefrom, but secured thereto with any suitable means.

17 designates a seat or recess within the sleeve 16, in which the free end 18 of the stem 19 freely slides, said stem having its lower 95 portion threaded and provided with the lock or jam nuts 20, which can be adjusted so as to lengthen or shorten the extent of move-

ment of the stem 19, as will be hereinafter explained.

21 designates a tube which is open at its upper portion and has its lower extremity 5 screwed or otherwise removably secured to the ring 22, which has a passage therethrough, and whose lower portion forms a valve-seat for the valve 8.

It will be apparent that the ring 22 may be

- 10 made integral with the casing 1 and the contiguous wall of the oil-chamber 14, or the parts can be made separate and secured together by any suitable means, according to requirements. It will further be evident that
- 15 while in Fig. 1 I have shown the gauze or straining device 6 as located between the sleeve 16 and the lower portion of the tube 21, if desired the gauze may be located exterior to the lower portion of said tube with- 20 out departing from the spirit of my invention, it being in either case advantageously removable with said tube for cleaning or re-newal.

23 designates a coupling which is screwed 25 or otherwise secured to the upper portion of the stem 19, said coupling having its upper portion secured to the diaphragm-stem 24, whose upper portion is provided with a flange 25, which contacts with the upper portion 26 30 of the diaphragm 27, the latter having a lower wall 28, through which the stem 24 freely passes, it being understood that there is a passage 29, whereby communication is had between the diaphragm-chamber 30 and the 35 vapor-chamber 31, within which the coupling 23 is located.

32 designates a diaphragm-spring chamber in which is located the coil or other spring 33, the lower portion of which contacts with 40 the flange 25, while its upper portion contacts with the under side of the adjusting-screw 34, which can be readily manipulated from the exterior for varying the tension of the spring 33.

45 35 designates an arm extending from the coupling 23, to which is pivotally attached the vapor-valve 36, the latter consisting of a rod passing upwardly through the guide 37, it being apparent that the upper extremity 50 of 38 of the valve opens or closes, according to requirements, the passage 39, wherefrom the vapor is led by the pipe 40 downwardly to the regenerator 41, and it being further understood that the vapor is led into the vapor-chamber through the pipe 42 from the generator 43.

The operation of the governor or fluid-pressure regulator seen in Fig. 1 in communication with the lamp seen in Fig. 2 is as follows:

- 60 The casing or reservoir 1 having been filled to the desired level through the filler 2 it will be seen that the hydrocarbon flows from the pipe 15 through the valve 44, where it divides, a portion of the hydrocarbon flowing through 65 the pipe 45 downwardly through the lower

portion 46 of the generator 43, wherein the oil is vaporized, the vapor flowing out through the pipe 42, hereinbefore referred to, and exerting its pressure in the vapor-chamber 31, said vapor flowing past the vapor-valve 36 and 70 flowing outwardly through the pipe 40 downwardly into the regenerator 41 and from thence through the nozzle 47 and commingling-tube 48 to the burners 49.

I have purposely omitted to describe in detail the precise construction of the burners 49, the starting devices, the generator and regenerator, and their adjuncts, since I herein make no claim to them, and the foregoing are fully described in my contemporaneously-pending application, Serial No. 154,970, filed April 30, 1903, of which this case is a division.

The operation of the governor is as follows: It will be understood that the oil-valve 8 regulates the passage of the oil or hydrocarbon 85 to the pipe 15 and that said valve is controlled by the compression-spring 10. The vapor-inlet to the vapor-chamber 31 is through the pipe 42, and the outlet from the vapor-chamber is governed and controlled by the vapor-valve 36, which controls the flow of the vapor through the pipe 40. This vapor-valve 36 acts in unison with the compression-spring 33, which abuts against the diaphragm, which causes the proper movement of the connections 24, 23, and 19, which action either compresses the spring 10 or permits of its expansion, thereby opening and closing the oil-valve 8 and permitting the hydrocarbon to flow past said valve or stopping the flow of the same 100 therethrough. While the vapor-valve 36 acts in unison with the hydrocarbon-valve 8, its office is entirely independent and its operation separate and distinct therefrom, for when the pressure in the governor exceeds the point at 105 which it is set the spring above the diaphragm moves the connections 24, 23, and 19, thereby allowing the hydrocarbon-valve 8 to move by the expansion of the hydrocarbon-spring 10, which closes the hydrocarbon-valve 8 and shuts 110 off the supply of fluid to the vaporizer. Now when the hydrocarbon-valve 8 refuses to respond to the action of the compression-spring 33, resting on the diaphragm below it, owing to any dirt being on the face of the valve 8, 115 a disarrangement of the spring 10, or for any other cause, and the pressure continues beyond the point set, then the box-diaphragm will still further expand and cause the vapor-valve stem 36 to become seated, which immediately 120 cuts off the supply of vapor to the pipe 40, thereby extinguishing the light, when vaporization ceases in the generator and the pressure is at once destroyed, owing to the stoppage 125 of the vapor to feed the burner.

It will be apparent that while I have shown in Fig. 1 the preferred construction of my governor or fluid-pressure regulator and have indicated the diaphragm, vapor-valve, and its adjuncts as being in the upper portion of 130

the apparatus, and the oil-chamber, oil-valve, and oil-spring as being in the lower portion thereof, I do not desire to be limited thereto in every instance, for it is apparent that changes may be made in the manner of constructing and assembling these parts by those skilled in the art which will come within my invention, and I reserve to myself the right to make all such changes as fall within the scope of the same.

Having thus described my invention, what I claim as new, and desire to secure by Letters Patent, is—

1. In a governor adapted to regulate combustion in a vapor-lamp, a reservoir, a generator, a casing forming part of said reservoir, a valve in said casing for controlling the flow of hydrocarbon through said reservoir to said generator, a second valve in said casing for controlling the flow of vapor toward the point of combustion and a pipe leading from said generator to said casing.

2. In a vapor-burning device, a reservoir, a liquid-hydrocarbon chamber below said reservoir, a vapor-chamber above said reservoir, a valve controlling the flow of liquid from said reservoir to said liquid-chamber, a second valve controlling the flow of vapor from said vapor-chamber to the point of combustion and a diaphragm operatively connected with both said valves, the stem of said liquid-controlling valve passing through said reservoir.

3. In a vapor-burning device, a horizontally-disposed reservoir and a vertical valve-casing connected with and extending downwardly below said reservoir, separate valves in said cas-

ing controlling the flow of both liquid and vaporized hydrocarbon therethrough, automatic vapor-controlled means for operating said valves and a valve connection passing through said reservoir.

4. In a vapor-burning device, a reservoir, a valve-casing directly connected to said reservoir, a valve in said casing controlling the flow of hydrocarbon therethrough, a hood enclosing said reservoir and said casing whereby radiation therefrom is reduced, said casing having an aperture and a closure therefor which extends outside of said hood.

5. In a vapor-burning device, a hydrocarbon-reservoir, a generator, tubular connections leading from said reservoir to said generator and from the upper part of said reservoir to said burner and means working within said reservoir and actuated by the pressure of the generated vapor for controlling the flow of vapor from said generator to said burner.

6. In a vapor-burning device, a reservoir, a generator, a burner, tubular connections from said reservoir to said generator, and from said generator to the upper part of said reservoir, means providing a passage from said reservoir to the burner and means working within said reservoir and actuated by the pressure of the generated vapor for controlling the flow of hydrocarbon from said reservoir to said generator and the flow of vapor to said burner.
